VOLTAGE REGULATOR

Eugene Mittelmann, Chicago, Ill., assignor to Illinois Tool Works, Chicago, Ill., a corporation of Illinois

Application March 13, 1946, Serial No. 654,200

4 Claims. (Cl. 323—45)

1

The present invention relates to an apparatus and method for maintaining substantially constant filament voltage for an electronic power tube.

High power electronic or vacuum tubes, such as used in high frequency heating apparatus and in radio transmitters, require a relatively large amount of filament power. A constant voltage power transformer capable of handling that amount of power is quite expensive.

The present invention contemplates the use of a regulatory control circuit by which deviations from a constant voltage supplied by a low power voltage transformer are compared by a bridge circuit to a voltage supplied by a variable voltage high power transformer to control the voltage applied by the high power transformer to the filaments of the electronic tubes.

It is, therefore, an object of the present invention to provide an improved apparatus and method for maintaining substantially constant the filament voltage of electronic power tubes.

Other and further objects of the present invention will become apparent by reference to the following description taken in connection with the accompanying drawing wherein the single figure is a schematic diagram of a control circuit for regulating the filament supply voltage for electronic power tubes.

In accordance with the present invention the filament supply voltage for the electronic power tubes is controlled by an adjustable, variable voltage power transformer, or other variable voltage supply device, which is adjusted by a control circuit. This control circuit utilizes two vacuum tubes V_1 and V_2 arranged in a bridge circuit including anode resistors Z_1 and Z_2 connected between the anodes of the vacuum tubes V_1 and V_2 and the positive terminal of a source of anode voltage.

The vacuum tubes V_1 and V_2 may have a common cathode bias resistor Z connected to ground. Between the balance points of the bridge circuit which are located at the anodes of the vacuum tubes V_1 and V_2 there are connected two circuits including relays R_1 and R_2 . The circuit including the relay R_1 includes a unilaterally conductive device or contact rectifier CR_1 . Another circuit includes the relay R_2 and another similar contact rectifier CR_2 connected to be conductive in the opposite direction to rectifier CR_1 .

The grid of the vacuum tube V_1 is provided with a grounded grid resistor Z_3 . The grid is connected to a unilaterally conductive device such

2

as a contact rectifier CR_3 which is connected to one terminal of a voltage divider or potentiometer P_1 having its movable contact connected to ground. The voltage divider P_1 is arranged so as normally to be in parallel with the secondary winding W_2 of a small, low current constant voltage transformer T_1 having a primary winding W_1 formed in two sections separated by a shunt core member. The transformer T_1 may however be of any other suitable type of constant voltage transformer.

One portion of the primary winding W_1 is closely coupled to the secondary winding W_2 and the other portion of the primary winding W_1 is 15 closely coupled to a tertiary winding W_3 which is shunted by a capacitor C . The primary winding of the transformer T_1 is energized from alternating current conductors L_1 and L_2 .

The vacuum tube V_2 is provided with a grounded grid resistor Z_4 and the grid is connected to 20 a contact rectifier CR_4 . The contact rectifier CR_4 is connected to one terminal of a voltage divider or potentiometer P_2 having its adjustable contact connected to ground. The voltage divider P_2 is connected across a secondary winding 25 of a transformer T_2 which is energized from the output of a transformer T .

The transformer T is of the variable voltage type and has an adjustable contact which is 30 moved to the proper position by a motor controlled in accordance with the operation of the vacuum tubes V_1 and V_2 . The transformer T is connected across the alternating current lines L_1 and L_2 and supplies energy to the transformer T_2 and a transformer T_3 having its secondary winding connected to the filament circuit of the power tubes. The transformer T_2 therefore supplies to the grid circuit of the vacuum tube V_2 35 a voltage proportional to the voltage supplied to the filaments of the power tubes.

The adjustable contact on the transformer T is actuated by a motor FM which has two inductive windings FM_1 and FM_2 and two capacitors FM_3 and FM_4 . The common juncture between 45 the two capacitors is connected to one of the alternating current lines such as L_1 and also to one of each of the pairs of contacts of the relays R_1 and R_2 . The common juncture between the inductive windings FM_1 and FM_2 is connected through a limit switch S_3 to the other alternating current conductor L_2 .

The limit switch S_3 is positioned so that it will be opened when the adjustable contact on the transformer T is moved to a position where the transformer no longer supplies sufficient output

voltage. The limit switch S3 is connected in parallel with the normally open contacts S2 of the manually operable switch S. The manually operable switch S which may be of the push button type is also provided with another pair of normally open contacts S1. The normally open contacts S1 are connected in parallel with the normally open contacts of a relay PR.

The relay PR is arranged to be energized in accordance with the conventional on-and-off control circuits (not shown) of the power tubes. Upon conditioning the power tubes for operation, the relay PR is operated to close its contacts and connect one terminal of the secondary winding of the transformer W2 to the voltage divider or potentiometer P1.

The circuit shown operates to compare the constant voltage supplied by the secondary winding W2 of the transformer T1 with the voltage supplied to the transformer T2. The secondary winding W2 of the transformer T1 is arranged to supply a constant voltage proportional to the voltage which is normally to be supplied to the filament circuit of the power tubes.

The voltage divider P1 is provided to adjustably preset the proportional amount of the constant valued voltage which is applied to the vacuum tube V1. Similarly an adjustably presettable, proportional amount of the alternating current output voltage of the transformer T2 is applied through the voltage divider P2 to the grid of the vacuum tube V2. An increase in the control voltage of the grid circuit of V2 will cause the relay R2 to be operated which thereby will close its contacts to cause the motor FM to move the adjustable contact on the transformer T until the voltages supplied to the two vacuum tubes V1 and V2 are again balanced.

Similarly if the voltage applied to the grid circuit of the vacuum tube V2 is less than that applied to the grid circuit of the vacuum tube V1, the relay R1 will be actuated so that its contacts cause the motor circuit FM to close to cause the adjustable contact on the transformer to move in the opposite direction until the balanced condition has been restored.

If desired, an increased tube life may be obtained by reducing the voltage supplied to the filaments of the power tubes by the transformer T3 to a value somewhat under the rated value. This can be accomplished by adjustment of the voltage dividers P1 or P2. Of course any other desired level of constant filament voltage may be obtained. The voltage divider P1, for example, has a certain portion thereon connected in series with a circuit including the contact rectifier CR3 and the impedance Z3 so that a certain direct current bias is applied to the grid of the vacuum tube V1. The grid of the vacuum tube V2 is similarly supplied with direct current bias which varies in accordance with the potential output of the transformer T2.

The circuit for the automatic control of the output voltage of the transformer T is normally inoperative until the power tube equipment which it is associated with is placed in operation so that the control circuits therefor operate the relay PR to close its contacts. The contacts of the relay PR will set the circuit for automatic operation. In order initially to set the filament voltage before the high tension voltages are applied to the power tubes, the manual switch S is actuated. Actuation of the switch S closes the switch contacts S1 so as to connect the secondary winding W2 of the transformer T1 to the voltage

divider P1. Operation of the switch S also closes contacts S2 so that a circuit is prepared for the motor FM if the limit switch S3 is open.

The closing of the switch S therefore supplies power to the vacuum tube V1 which causes the relay R2 to close its contacts thereby to initiate operation of the motor FM which moves the adjustable contact on the transformer T away from the limit position. When the adjustable contact on the transformer T has been moved to a position where the output voltage of that transformer is in the preset proportion to the output voltage of the secondary winding W2 of the transformer T1, the vacuum tube V3 will have a grid circuit potential such that the relay R2 is deenergized. The relays R1 and R2 operate only as long as a potential difference exists between the balance points of the bridge which are located at the anodes of the two vacuum tubes V1 and V2. The push button switch thereupon may be released. When, thereafter, the control circuits associated with the power tubes are energized, the relay PR will be actuated and the filament voltage will automatically be maintained constant.

Whenever the power tube equipment is shut down, the relay PR will open its contacts thereby removing the grid bias from the vacuum tube V1 and thus leaving the vacuum tube V2 energized. This condition causes the relay R1 to become closed so as to actuate the motor FM which will then move the adjustable contact on the transformer T back to its zero or preset low-valued position. At that position an adjustable abutment (not shown) on the adjuster for the transformer T opens the limit switch S3 thereby deenergizing the motor FM.

The circuit shown is connected to alternating current lines L1 and L2 at a point in advance of the usual high tension control switches for the power tube equipment so that upon interruption of the operation of the vacuum tube apparatus, control voltages will be supplied to the circuit shown to permit the circuit to be restored to its no-load condition.

From the foregoing it will readily become apparent to those skilled in the art that the device of the present invention is capable of handling a large amount of power without the use of relatively expensive or heavy constant voltage equipment. While the device for controlling the voltage output has been shown as being an adjustable tap transformer T, it will be understood that other adjustable voltage supply devices might be used in place thereof.

While for the purpose of describing and explaining the present invention, a single embodiment has been shown in the drawing, it is to be understood that such variations and modifications thereof are contemplated as may be commensurate with the spirit and scope of the invention defined in the appended claims.

This invention is hereby claimed as follows:

1. The combination for supplying substantially constant alternating current voltage to a load comprising a source of alternating current, adjustable voltage power means interposed between said source and said load, a motor for adjusting said device, a balanced bridge control circuit for controlling the operation of said motor, means for supplying to said bridge circuit a potential proportional to the potential supplied to said load, and means for supplying to said bridge circuit a constant potential alternating current having a value equal to the rated voltage to be supplied to said load.

2. An apparatus for supplying power to the filaments of vacuum tubes at substantially constant potential comprising a source of alternating current, a variable voltage power transformer having voltage adjustment means and connected to said source of alternating current for supplying power to said filaments, a motor for adjusting the position of said adjustment means, a bridge circuit for controlling the operation of said motor, a connection between said power transformer and one arm of the bridge circuit to supply thereto a voltage proportional to the voltage applied to the filaments by said power transformer, a constant voltage transformer connected to said alternating current source, the constant voltage transformer having a secondary winding arranged to supply to another arm of the bridge circuit a voltage proportional to the rated filament voltage of said vacuum tubes, a relay having a pair of contacts interposed between said bridge circuit and said constant transformer, said relay being adapted to be connected to the control circuit of the power tubes to energize and deenergize the last mentioned arm of the bridge circuit in response to the control circuit of the power tubes, a limit switch arranged to be opened by the adjustment means of said power transformer at a preset low voltage output position, and manually operable switch means for bridging the contacts of said limit switch and the contacts of said relay manually to preset the adjustment means of the power transformer prior to the operation of the power tubes.

3. In a system for supplying relatively large power at a substantially constant alternating current voltage from a source of alternating current subject to voltage variations, the combination comprising a circuit having an input, an output, and voltage adjustable means connected therebetween, said voltage adjustable means having mechanically operable adjustment means, a motor for adjusting said adjustment means, a

- space discharge tube bridge circuit having a pair of space discharge tubes, means for supplying to one of said space discharge tubes a potential proportional to the potential supplied to said output, means for deriving from said input a constant valued potential proportional to the predetermined value of the voltage desired to be supplied by said output, means for supplying said constant valued potential to the other of said tubes, and means responsive to said bridge circuit for controlling the direction and extent of rotation of said motor in accordance with the direction and extent of deviation of the voltage of said output from said predetermined value.
- 15 4. The combination for supplying power at substantially constant alternating current voltage to a load comprising a supply source of alternating current of high power, means for supplying a constant voltage alternating current of low power, 20 equal in voltage to the voltage of the A. C. power to be supplied to the load, adjustable means for supplying power to the load from said source of alternating current of high power, means for comparing the alternating current voltage applied 25 to the load from the high power source with said constant alternating current voltage of low power, and means for continuously adjusting said adjustable means in response to the difference of the comparison to maintain substantially constant the voltage of the alternating current applied to said load from the high power source.
